UNITED STATES PATENT OFFICE.

NATHANIEL L. RIPLEY, OF BOSTON, MASSACHUSETTS.

DESIGN FOR A FINGER-RING.

SPECIFICATION forming part of Design No. 12,868, dated April 11, 1882.
Application filed March 2, 1882. Term of patent 3½ years.

To all whom it may concern.

Be it known that I, NATHANIEL L. RIPLEY, a citizen of the United States, residing at Boston, Suffolk county, State of Massachusetts, have invented and produced a new and original Design for Finger-Rings, of which the following is a specification, reference being had to the accompanying drawing, forming part thereof.

10 The drawing represents in perspective a ring containing my design.

The outer part of the ring is cut from its edges to present large facets *a* and intermediate small facets, *b*, leaving between them plane or flat surfaced oblong eight-sided panels, joined or abutted together at the angular corners between the ends and sides of the panels as represented in the drawing. These panels at one edge have a series of curved lines, *c*, surrounded by a crown-like ornamented border, *d*. The entire edges of these panels are ornamented, as shown.

I claim—

1. The design for finger-ring, herein shown and described, the same consisting of the facets *a b*, of different sizes, and eight-sided panels, having their angular corners placed end to end.

2. The design for finger-ring, shown and described, the same consisting of the facets *a b*, of different sizes, the eight-sided panels having their angular corners placed together, and the ornamented curved lines surrounded with a crown-like border above the curved lines.

In testimony whereof I have signed my name to this specification in the presence of two subscribing witnesses.

NATHL. L. RIPLEY.
